JOHN A. THOMAS, OF BUFFALO, NEW YORK, ASSIGNOR TO HIMSELF
AND HENRY J. MILLER, OF DUNKIRK, NEW YORK.

Letters Patent No. 61,894, dated February 5, 1867.

IMPROVEMENT IN MACHINES FOR POLISHING METAL TUBES.

The Schedule referred to in these Letters Patent and making part of the same.

TO ALL WHOM IT MAY CONCERN:

Be it known that I, JOHN A. THOMAS, of the city of Buffalo, county of Erie, and State of New York, have invented a new and improved Machine for Reaming and Polishing Metal Tubing for Pumps, and other purposes; and I do hereby declare that the following is a full and exact description thereof, reference being had to the accompanying drawings.

Figure 1 is a central longitudinal section.

Figure 2 is an end elevation.

Figure 3 is a detached section of one of the clamping sockets.

Figure 4 is a detached view of one of the mandrels and cutters, *m c.*

Figure 5 is an elevation of a portion of the middle bearing-frame K attached, showing the boxes L for the tubes.

Like letters designate corresponding parts in all of the figures.

My invention has for its object the reaming and polishing of tubing for pump barrels and other purposes in a cheap and expeditious manner, and consists in the combination and arrangement of a series of stationary mandrels on a sliding frame with a corresponding series of the tubes to be reamed, so supported and connected by and with the frame and driving mechanism as to revolve rapidly around the mandrels while the latter are fed to the same, as hereinafter set forth.

A is a horizontal bed-frame, supported on standards or otherwise, to which is attached the upright supporting frame B, which is preferably of circular form, as shown in fig 2. In the centre of this frame is hung, in a suitable box or bearing, the arbor C, provided with two gear-wheels, D E; the former for receiving motion from a driving-pinion, F, on the shaft of the cone-pulley G; the latter being of greater size for imparting rapid motion to the several pinions, H H, arranged at equal intervals around and meshing with it. Each of the last-named pinions is fixed to an arbor, which has its bearing in the frame B, through which it extends, and is provided on its opposite end with a screw socket, J, fitted to receive the male end of the tube or pipe I. As pipes of this description are usually provided with a screw at one end for connecting the sections together, it is only required that sockets for the pinions should be provided to fit the various sizes of pipe to be reamed; but when the pipe is not so provided it may be held in the socket by clamping it by set-screws *i i*, as shown in fig 3. The pipes I are furnished with bearings at their opposite ends by means of the circular bearing-frame K, figs. 1 and 2. This frame is provided with apertures corresponding in number and position with the pipes, through which they pass freely, and are received in the boxes L L, which are bolted to the outer side of the frame. The ends of the pipes fit snugly, but turn in these boxes, which hold them steadily and prevent vibration while revolving. The frame K is adjustable on the bed-frame to adapt it to receiving pipes of different lengths. The mandrels *mm* are rigidly secured at their further ends to a frame or carriage, O, (fig. 1,) being arranged in positions which correspond with those of the pipes I I. This carriage slides on ways of the frame A, being fed by the screw of the revolving arbor C. The mandrels *m* are provided with burrs or cutters, which are screwed or otherwise attached to the ends, as at *c*, fig. 4. As the tubes I are rapidly revolved around these stationary cutters, they are reamed or bored out smoothly as fast as they are fed through by the advancing of the carriage O. When bored through, the carriage O is run back, withdrawing the mandrels, when the tubes are unscrewed from the pinion sockets and removed, a new set being inserted in their place. In this simple manner twelve pieces of tubing, or more or less, according to the size of the machine, may be bored in the time ordinarily required to bore one. For some purposes the tubes require polishing on their interiors also. This is effected in the same machine by removing the burr cutters *c* from the mandrels, and substituting a polishing head in the place of each. The polishing head is composed of a screw shank, fitting into the end of the mandrels, having a head upon which are fitted several spring-plates, held by a ring chuck, or its equivalent. These plates are provided at their ends with leather buffers for scouring. The speed of rotation may be increased by changing the driving-belt on the cone-pulley, and, by the united pressure of the several springs, the polishing is very rapidly and effectually done. The entire arrangement and construction of the machine is productive of the result arrived at by the invention, viz, the cheap and rapid reaming and polishing of metal tubing as it is simple, compact, and not liable to get out of order by use.

What I claim as my invention, and desire to secure by Letters Patent, is—

The combination of the series of stationary cutter mandrels *m m*, on the sliding carriage *O*, with the pinions *H H*, and their sockets *j j*, adjustable bearing-frame *K*, and driving-wheels *D E*, arranged and operating substantially in the manner and for the purpose set forth.

In witness whereof I have hereunto signed my name in the presence of two subscribing witnesses.

JOHN A. THOMAS.
